UNITED STATES PATENT OFFICE.

JOHN H. FOOTE, OF JAMAICA, NEW YORK.

BOILER-FURNACE.

1,323,038.

Specification of Letters Patent. Patented Nov. 25, 1919.

Application filed September 12, 1918. Serial No. 253,708.

To all whom it may concern:

Be it known that I, JOHN H. FOOTE, a citizen of the United States, residing at Jamaica, county of Queens, and State of New York, have invented certain new and useful Improvements in Boiler-Furnaces, of which the following is a specification.

Reference may be had to the accompanying drawings, and the reference characters marked thereon, which form a part of this specification. Similar characters refer to similar parts in the several figures therein.

This invention relates to arches for boiler furnaces and is particularly adapted for the rear arch of a furnace for an ordinary flue-boiler.

In boiler-furnaces of the type to which this invention more particularly relates it is customary to form a rear arch extending from side wall to side wall of the furnace walls, and from the rear furnace wall to the rear end of the boiler, whereby the heated gases from the combustion chamber are deflected and directed back through the flues of the boiler. Such a rear arch has been commonly made of a series of elongated fire-brick blocks arranged side by side which blocks are subjected on their inner or lower sides to the intense heat of said gases. Much difficulty has been experienced in properly supporting such an arch, particularly along the inner end of the arch adjacent to the end of the boiler. Various means have been devised and employed for providing the necessary support for the inner end of such an arch, all requiring the use of devices separate from, and added to, the construction proper of the furnace and arch, one form of such supporting means or mechanism being

shown in Letters Patent heretofore granted to me, No. 753,059, dated February 23, 1904, for boiler furnace. While the device shown in my said patent successfully accomplishes the desired result, it will be apparent that the use of the added supporting-bar for the front portion of the arch requires the formation of grooves in the inner ends of the fire-brick blocks whereby said inner ends are weakened and rendered more liable to fracture; and it is difficult in such a construction to repair or replace a broken block without taking down practically the entire arch.

The principal objects of the invention are

to provide a more durable arch, an arch which can be quite readily repaired, and to eliminate the use of additional supporting devices for sustaining the end of the arch which is adjacent to the end of the boiler.

Other objects will appear in connection with the following description.

Figure 1 of the drawings is a central longitudinal section of my improved furnace with the front portion, which may be of any known construction, broken away, the boiler being shown in side elevation.

Fig. 2 is a vertical cross-section taken on the broken line 2—2 in Fig. 1.

Fig. 3 is a view in isometrical perspective of the arch detached, the arch being formed of a plurality of elongated bricks or blocks.

Fig. 4 is a similar view of one of the bricks or blocks detached.

Fig. 5 is a view in cross-section taken on the broken line 5—5 in Fig. 1, illustrating the manner in which the key-block is raised or removed in the operation of replacing a broken block.

Referring to the drawings wherein the invention is shown in preferred form, the bed, 80 1, side walls, 2, and end wall, 3, of the furnace are preferably made of fire-brick in the usual manner except that said rear wall is formed with a prominent seat, 4, adapted to receive and support the outer end portions 85 of the elongated fire-brick arch-blocks, 5, 5^a and 5^b, which make up the rear arch of the furnace.

I have shown the blocks, 5, which form the lefthand part of the arch as viewed from the front or in Fig. 3, rabbeted to overlap one another from the middle of the arch to the left-hand side wall of the furnace, the outermost of said blocks being rabbeted to receive and overhang said side wall.

The blocks, 5^a, which form the right-hand part of the arch are in like manner rabbeted to overlap one another from the middle of the arch to the right-hand side wall of the furnace, the outermost of said blocks being 100 rabbeted to receive and overhang said side wall.

The innermost block, 5, and the innermost block, 5^a, are rabbeted along their upper inner edges to receive the head of a T-shaped key-block, 5^b, which overhangs both of said innermost blocks, 5, and 5^a, as shown.

The blocks may be further interlocked by

forming upon the sides of certain of the blocks small bosses or studs, 7, adapted to engage correspondingly located oppositely disposed recesses, 15, in the neighboring 5 wall of the next adjacent block.

The outer end portions, 5^a, of the arch-blocks are made much more heavy than has been customary, and are extended outwardly much farther than has been customary, whereby the portion of the block which is supported by and overhangs the seat, 4, is of approximately the same weight as the portion of the block between the rear wall, 3, and the neighboring end, 8, of the 10 boiler, 9.

The inner ends of the several blocks, 5, rest against the neighboring end of the boiler above the line of the flue-openings, and at a substantial height above the plane 20 of the seat, 4, on the end wall of the furnace, whereby tendency to a downward swinging movement of the inner end of the arch is resisted by engagement of the inner end of the arch with the neighboring end of the boiler 25 due to the fact that such a downward swinging movement would cause the inner end of the arch to traverse a curved path intersecting the end of the boiler.

As the blocks are approximately balanced 30 upon the seat, 4, due to the distribution of weight above referred to, but little force is required to prevent such downward swinging movement of the inner end of the arch.

As a further means for preventing any 35 such downward swinging or deflection of the inner end of the arch, I provide the seat-overhanging portions of the blocks, 5, with vertical bolt-receiving openings, 10, which may be formed in the blocks in any known 40 manner, but which are shown as preferably formed by complementary grooves in the neighboring sides of two adjacent blocks; and I mount in the end wall, 3, of the furnace, anchor-bolts, 11, adapted to project upwardly through said openings, 10, and having on their upper ends nuts, 12, adapted to be screwed down into engagement with the upper side of the seat-overhanging portions 45 of the respective blocks. The blocks are thus held securely in position under all conditions of use.

Should the key-block, 5^b, become broken or defective it can readily be removed by loosening such of the nuts, 12, as lock it in 55 position, whereupon it can be raised, or it can be chipped or broken until it can be removed, whereupon a new key-block may be inserted in the arch in place of the defective one.

60 If one of the other blocks in the arch becomes broken or defective, the key-block can be first removed, whereupon permitting access to, and the removal of, a defective block on one side of the middle of the arch 65 and replacement thereof by a new block,

without disturbing the blocks on the other side of the middle of the arch.

In thus substituting a new block without dismounting the whole arch, the bosses or studs, 7, may be removed where they interfere with the insertion of the new block. 70

The inner ends of the arch-blocks, 5, are preferably chamfered on the upper side as at 13, forming a groove between the end of the boiler and the inner ends of the blocks 75 which groove is filled with cement, 14, forming a tight joint between the inner end of the arch and the end of the boiler.

By approximately balancing the blocks upon the seat, 4, and having the side members of the interlocked blocks overhang and rest upon the side walls of the furnace, the inner end of the arch is rendered self-supporting except for its engagement with the side walls of the furnace and the end of the 80 boiler, and but slight assistance is needed from the anchor-bolts, 11, to securely hold the outer portions of the arch in position. 85

For the cement, 14, I preferably employ asbestos fiber cement, as it accommodates 90 itself to the contraction and expansion of the joint between the inner end of the arch and the end of the boiler.

To more uniformly distribute the holding force of the nuts, 12, and to prevent injury 95 to the blocks, I prefer to interpose between the nuts and the respective blocks, plates or washers, 16.

What I claim as new and desire to secure by Letters Patent is:

100

1. The combination with the walls of a boiler-furnace; and a boiler mounted within said walls, a wall of the furnace opposite the end of the boiler having an arch-block-supporting seat; of an arch-block extending between said furnace-wall and the neighboring end of the boiler with a portion of said block supported by and overhanging said seat, said seat-overhanging portion of said block being approximately equal in weight to the portion of said block between said furnace-wall and the neighboring end of the boiler; and an arch-block-bolting member mounted in said furnace-wall in connection with said seat-overhanging portion of said block. 105

110

2. The combination with the walls of a boiler-furnace; and a boiler mounted within said walls, a wall of the furnace opposite the end of the boiler having an arch-block-supporting seat; of an arch-block extending between said furnace-wall and the neighboring end of the boiler with the inner end of said block adjacent to said end of the boiler at a point substantially higher than the horizontal plane of said seat, said inner end of the block being chamfered on its upper side to form between the block and said end of the boiler a cement-receiving groove, said block having a portion thereof supported by 125 130

- and overhanging said seat approximately equal in weight to the portion of said block between said wall and said end of the boiler; a body of cement occupying said groove 5 between the inner end of the block and the neighboring end of the boiler, and a connection between the seat portion of the furnace-wall and the seat-overhanging portion of said block.
- 10 3. The combination with a boiler; of a furnace within which said boiler is mounted, having side walls, and an end wall opposite an end of the boiler, said end wall having an arch-block-supporting seat; of 15 an arch formed of interlocked arch-blocks extending from side wall to side wall of the furnace, and from said end wall of the furnace to the neighboring end of the boiler with the end blocks of said arch overhanging 20 and supported by said side walls of the furnace, and the inner ends of said blocks in engagement with said end of the boiler; said blocks having portions supported by and overhanging said seat approximately equal 25 in weight to the portions of said blocks between said wall and the end of the boiler, the inner end of said arch being self-supported save for its engagement with the side walls of the furnace and said end of the 30 boiler.
4. The combination with the walls of a boiler-furnace; and a boiler mounted within said walls, the wall opposite the end of the boiler having an arch-block-supporting 35 seat; of a plurality of arch-blocks each extending between said furnace-wall and the neighboring end of the boiler, and having a portion supported by and overhanging said seat, certain of said blocks being provided 40 with a vertical bolt-receiving opening formed between neighboring blocks; an anchor-bolt mounted in said end wall of the furnace projecting upwardly through said bolt-receiving opening between neighboring 45 blocks; and a nut on the upper end of said anchor-bolt in engagement with said seat- overhanging portions of said neighboring blocks.
5. The combination with a boiler; of a furnace within which said boiler is mounted, having side walls, and an end wall opposite an end of the boiler, said end wall having an arch-block-supporting seat; an arch formed of interlocked arch-blocks extending from side wall to side wall of the 50 furnace, and from said end wall of the furnace to the neighboring end of the boiler with the end blocks of said arch overhanging and supported by said side walls of the furnace, and the inner ends of said blocks 55 in engagement with said end of the boiler, said blocks having portions supported by and overhanging said seat approximately equal in weight to the portions of said blocks between said wall and the end of the boiler, 60 said seat-overhanging portions of the blocks being formed with vertical bolt-receiving openings; anchor-bolts mounted in said end wall of the furnace projecting upwardly through said bolt-receiving openings in the 65 blocks; and nuts and washers on the anchor-bolts in engagement with said seat-overhanging portions of the blocks.
6. The combination with a boiler; of a furnace within which said boiler is mounted, having side walls, and an end wall opposite an end of the boiler, said end wall having an arch-block-supporting seat; of an arch comprising a series of arch-blocks extending from side wall to side wall of the 70 furnace, and from said end wall of the furnace to the neighboring end of the boiler, one of said blocks being T-shaped and overhanging the neighboring blocks on either side, the other blocks overhanging one another from said key-block to the respective side walls of the furnace, the outermost of 75 said blocks overhanging the respective side walls of the furnace.

In testimony whereof I have hereunto set 90
my hand this 5th day of Sept., 1918.

JOHN H. FOOTE.
